HUM AND NOISE REDUCTION

John H. De Witt, Nashville, Tenn.

Application January 31, 1936, Serial No. 61,634

26 Claims. (Cl. 250—17)

My present invention relates to the reduction of hum and noise in high frequency systems and particularly in radio transmitters.

Modern practice dictates, for economy, the use of commercial alternating currents for energizing the cathodes and filaments of the tubes in the various stages of a radio transmitter. In addition, it has proven highly practical to polarize the plates of the vacuum tubes employed in transmitters with rectified low frequency alternating current. However, concomitant with the use of alternating current energization circuits there appears in the output of the transmitters objectionable noise, usually in the form of hum corresponding in frequency to the fundamental and one or more harmonics of the low frequency energizing source. To reduce this hum it has been proposed, in addition to filtering, to make use of polyphase filaments and to excite them from a source of polyphase current. While such action has proven a partial solution of the problem, it nevertheless leaves much to be desired, especially, for example, in connection with the utilization of present day high fidelity receivers; for, with such receivers, transmitter noise is still undesirably manifest.

An object of my present invention is, therefore, to provide a noise and hum reduction system for high frequency circuits in general and for transmitters in particular, which system will reduce hum and noise to a much lower level than that attainable heretofore, as far as I am aware. This object is effected by employing feed-back circuits which tend to cause a disproportionate reduction in hum and noise generated throughout the various stages of the system, which, in the case of a radio transmitter, include the radio frequency stages.

The use of degenerative feed-back in active low frequency networks has for some time been recognized as a means of reducing hum, noise and modulation products as well as accomplishing other desirable results such as stabilizing the gain. The application of this principle is relatively simple in audio frequency amplifiers in which there is a small amount of phase shift, but its application to a complicated circuit such as a radio transmitter presents difficulties, especially as regards oscillation production at an undesired, troublesome frequency. Accordingly, a further object of this invention is to provide a simple, efficient and inexpensive hum, noise and distortion reducing circuit for radio transmitting apparatus which circuit will not produce undesired oscillations.

Briefly, my present invention makes use of a feed-back system which reduces undesired noise and distortion without generating an independent oscillation. For this purpose, an ideal feed-back circuit would be one in which the phase does not shift appreciably over a frequency range from zero to infinity. Such a circuit would have no tendency to oscillate with any amount of degenerative feed-back. In any circuit in which the phase around the feed-back loop changes 180°, oscillations will take place providing the gain around the loop at the frequency at which the phase shift is 180° is equal to or greater than unity. In a radio transmitter employing various stages of audio amplification, modulation, radio frequency, power amplification, etc., the phase usually shifts 180° at frequencies lying near both edges of the audio band. As a result, when feed-back is applied, oscillations take place at one or both of these frequencies.

According to my invention this unwanted result is prevented in that two wave paths are provided, one being the transmitter in which it is desired to reduce noise and distortion. The other wave path is combined with the first and is arranged to have a gain when considered from the transmitter input to its output equal to or greater than the gain in the transmitter or first path. Moreover, the second wave path is so designed as to have very little phase shift over a frequency range somewhat wider than that of the transmitter. The two paths are so connected that their output voltages would be in phase over the wanted frequency range. The voltage or current fed back to the transmitter is the vector sum of the voltages or currents from the two paths, as a consequence of which at whatever frequency the phase through the transmitter shifts 180° the feed-back is neutralized as the currents in the two paths are out of phase and thus "singing" is prevented. In a preferred form of my invention, a simple filter is placed in the second path so as to allow its operation only near the frequencies at which oscillations would take place. The reason for this is to prevent degeneration of the second path over the wanted frequency range of the transmitter. However, this degenerative action through the second path is very desirable near the frequencies at which it is tuned, as it prevents unwanted distortion products which would be nearly in phase at these frequencies from being amplified by the transmitter.

That is to say, my present invention employs two wave paths of approximately equal gain. In a preferred modification, one path is the trans-

mitter itself and the other a simple amplifier or other apparatus having relatively little phase shift over the frequency range of the main path. The two paths are so arranged that their outputs are in phase over the wanted range and are out of phase at whatever frequency the transmitter has a tendency to oscillate. As a result, when the phase through the transmitter shifts 180 degrees from its normal condition, the feed-back balances out and singing is prevented. In practice, simple filters have been used in the second path to allow it to operate only near the frequencies at which the transmitter tends to sing.

15 My present invention will be described in greater detail in conjunction with the accompanying drawings which are not to be considered as imposing any limitations upon it, for it is to be clearly understood that the drawings illustrate 20 only some of the many possible arrangements employing the fundamental principles herein given.

16 In the drawings, Figures 1 and 2 are block diagrams illustrative of the general principles employed in my invention and Figure 3 is a wiring diagram partially in block form of a complete 25 radio transmitter employing circuits for reducing hum, noise and distortion according to my invention.

30 Referring to Figure 1, the signal to be broadcast coming in on the transmission line TL is fed to the radio transmitter RT and radiated over the antenna A. The radio transmitter RT includes audio, radio frequency generator, modulator, and power amplifier stages, which in and 35 of themselves introduce distortion due, among other things, to imperfect tube and circuit characteristics. In addition, because of alternating currents employed to energize the cathodes in 40 the radio transmitter RT and due to the use of rectified alternating currents for supplying the anodes of the various tubes in the radio transmitter RT there will be present, in the output of 45 the radio transmitter, undesirable hum which is radiated as one of the products of modulation over the antenna A. To reduce the distortion and hum components, a portion of the transmitter output is rectified in the rectifier R and fed back through hum amplifier HA in degenerative phase 50 to the audio frequency input circuit of the transmitter RT. It will be found that that degenerative feed-back which causes an appreciable reduction in hum is accompanied by a reduction in gain which may be made up for by an additional 55 stage of audio frequency amplification, in the radio transmitter. As the cost of such a stage of amplification is relatively slight, compared to the cost of the entire transmitter and the advantages to be gained by the use of this invention, it is not objectionable.

60 However, the degenerative feed-back which causes appreciable reduction in distortion and hum is also accompanied by parasitic oscillation generation at some undesired frequency above or 65 below the usable modulation band of the transmitter. This occurs because the rectifier R and the distortion and hum amplifier HA, while adjusted in combination with the radio transmitter RT to produce degenerative effects over the usable band of frequencies, operate regeneratively 70 at parasitic frequencies for which the integrated phase shifts of the stages in the radio transmitter, the rectifier R and the amplifier HA produce the condition or overall 180° phase shift 75 essential for regenerative action.

The foregoing defect is remedied by providing an additional network NW which produces zero phase shift over a range including the modulation range of frequencies and which produces essentially a 180 degree phase shift in parasitic 5 frequency oscillations so that at the combining point CP the parasitic oscillations fed back into the transmitter are reduced to such an extent as not to produce undesired singing or parasitic oscillation generation. 10

Figure 2 is a simplified arrangement of the apparatus diagrammatically shown in Figure 1 and is simplified to the extent that the need for a separate degenerative amplifier HA is eliminated. This is accomplished by connecting the network 15 NW, as shown, to one of the lower audio frequency stages of the radio transmitter.

Figure 3 is a wiring diagram of a preferred manner in which the principles of my present invention may be carried into effect and illustrates in greater detail the general arrangement 20 of Figure 2.

All of the apparatus shown in Figure 3 is usually found at the radio frequency transmitter.

An audio frequency signal coming in over the transmission line TL is fed through the transformer TF and resistance bridge RB to the audio frequency amplifier stage AS1. A portion of the output of the tube AS1 is fed through blocking condenser 2 to the control grid of audio tube AT 30 so as to permit of push-pull audio frequency excitation of the second stage of audio frequency amplification AS2. This stage includes the two vacuum tubes 4, 6 whose outputs are fed through transformer 8 to the modulator 10. The modulator 10 may be of any of the conventional types and serves to modulate the high frequency oscillations generated at the high frequency oscillator HFO and fed to the modulator 10 through the buffer amplifier BA. The buffer amplifier, if 40 desired, may contain frequency multipliers so as to produce the desired radiation frequency from a lower frequency high frequency oscillator. The output of the modulator 10 is fed through the radio frequency power amplifier 12 whose output 45 in turn is radiated from the antenna A. 35

The filaments or cathodes for the tube stages AS1 and AS2 as well as for the tube AT are energized from a suitable source of supply such as a 60 cycle commercial transformer 14, provided 50 with any suitable voltage reducing transformer system such as 14, 16, 18, 20. The various filaments are provided with filament heating transformers 18, 20, the midpoints of the secondaries of which are grounded, as illustrated. In addition, by-passing condensers 22, 24 are provided. The by-passing condensers 22, 24 and the mid-tap connections to the secondaries of the transformers, reduce to some extent hum due to application of alternating currents to the filaments or 60 cathodes of the tubes employed.

The buffer amplifier BA, the modulator 10 and radio frequency power amplifier 12 are supplied with, for example, 60 cycle commercial electricity from a three phase line 26. As shown, 65 a different phase is connected to each of the oscillator and buffer amplifier, modulator and power amplifier stages. This will not only serve to equalize the load on the power supply, but will also tend to cause a reduction in hum. If desired, 70 three phase or, in general, polyphase filaments may be employed in the buffer amplifier modulator and power amplifier stages so as to further lessen the ripple introduced into the final output by the commercial electricity supply source. 75

Despite all of the steps mentioned hereinabove to reduce hum or ripple and despite heavy filtering of the rectified plate voltage supplies, the hum present in the power amplifier output is still of such value as to produce objectionable noise in, for example, high fidelity receivers. The reduction of this hum to a negligible value according to my present invention is accomplished in the following manner.

10 A rectifier, here shown as of the full wave type employing vacuum tube rectifiers or diodes 28, 30, is provided with a tunable input circuit 32 coupled to the output of the power amplifier 12. The rectified output of the rectifier, which is a replica of the modulation applied to point TL as modified by the distortion and hum and noise through the transmitter including stages AS1, AS2, 10, 12, etc. is fed through resistor 34, ammeter 36 and by-passing condenser 38 across the 15 conjugate points 40, 42 of the resistance bridge RB. As a consequence the rectified current is unable to produce any reaction, or in other words, is not fed back over the transmission line TL to cause distortion, but is simply applied to the 20 control grid 44 of the vacuum tube stage AS1. Similarly, it is to be noted that by virtue of the connection of the secondary of transformer TF to the conjugate points 46, 48 no voltage will be impressed upon the rectifier R, but only upon the 25 grid electrode 44 of tube AS1.

Attention is directed to the fact that the tubes of each stage of the transmitter and the coupling circuits thereof do not introduce any appreciable phase shift in the alternating currents passing 30 therethrough to the antenna where the alternating currents under consideration are, in a properly designed transmitter, within a range of frequencies including the usable modulation range.

This condition is not affected by the rectifier 40 R, whose voltage output appearing across resistor 50 is fed back through the large condenser 38 to the grid 44 of stage AS1. The feed-back through the condenser 38 is in degenerative phase so that the signal, distortion and hum at the 45 output of the power amplifier 12 are reduced. This loss in signal is made up for by the inclusion of a stage such as AS1 which otherwise might not be present in the transmitter. It will be found that with this arrangement the hum and 50 distortion level in the output of the transmitter is reduced, but as this hum level is further reduced by increasing the degenerative feed-back, it will be found that undesirable parasitic oscillations are set up.

55 These parasitic oscillations are set up because of the fact that at points beyond the frequency range for which the transmitter does not produce phase shifts, each stage does introduce, at the parasitic frequencies, a certain phase shift depending upon the tubes and circuits employed. The integrated phase shift throughout the stages is such that for frequencies lying outside of the 60 usable frequency range the otherwise degenerative feed-back becomes regenerative, causing the 65 undesired oscillation generation.

This defect is remedied according to my present invention by providing another path from a lower stage of the transmitter, such as stage AS1, which will cause such cancellation of parasitic regeneration as to eliminate singing or oscillation at parasitic frequencies. This additional path, as illustrated in Figure 3, includes the conductor 60, by-passing condenser 62, resistance 64 to prevent short circuiting of the audio output of the stage 70 AS1 and circuits 66, 68 connected as shown. Usu-

ally it will be found that parasitic oscillation generation takes place at frequencies above the modulation range of the transmitter. Accordingly, the circuit 66, connected as shown, is provided which is made resonant above the working range of the 5 transmitter. The effect of this circuit is to introduce a voltage substantially equal and opposite to the parasitic voltage set up across the resistor 50. As a consequence, a parasitic voltage of no appreciable consequence is fed back through 10 condenser 38 and is of insufficient value to cause parasitic oscillation generation at the upper range of frequencies. This phase opposition effect is produced by virtue of the tuning of the circuit 66 and the value of the neutralizing voltage may be 15 adjusted by, for example, adjustment of resistor 64.

In a similar way circuit 68 is connected to the path including condenser 62 and resistor 64, but circuit 68 is tuned below the lower range of modulation frequencies and is added where there is a tendency for generation of parasitics at the lower frequencies producing an effect commonly known as "motor boating".

One of the actual circuits set up embodying 25 the principles of my present invention was as follows:

In a standard 5 kw. transmitter an audio amplifier stage utilizing two #53 tubes connected as a phase inverter was added ahead of the audio 30 system of the transmitter. A push-pull rectifier employing two #1V tubes was coupled to the transmitter output so as to provide audio feed-back voltage. A second feed-back path was provided in the form of a tap from the plate resistor 35 70 of the first audio stage AS1.

The circuit of the audio stage, the feed-back rectifier, and the feed-back neutralizing path which were added to the transmitter were as shown in Figure 3. It will be observed that the 40 second path is in the form of a tap from the plate of the first audio stage and current flows through this path and is fed into a parallel resonant circuit, the lower side of which is grounded. In this transmitter it was only necessary to neutralize a frequency of about 12,000 cycles because 45 of the fact that the phase shift at the low end of the frequency range is rather small at appreciable amplitudes. The circuit diagram shows that the output of the feed-back rectifier which 50 appears across 50 is connected in series with the voltage that would be built up across the tuned circuit near the "singing" frequency.

It is to be emphasized that this actual set up 55 as generally illustrated by Figure 3, is only one of the many possible arrangements of the fundamental principle of providing two wave paths.

Measurement of the transmitter by means of a cathode ray oscilloscope indicated that the phase shift through the entire system; that is, 60 from the grid of the first tube AS1 to the output of the feed-back rectifier R when the second path was short circuited was 90° at about 7,000 cycles, and 180° at about 12,000 cycles. Observations on feed-back systems indicate that distortion and 65 noise components which are fed back at a phase relation greater than 270° are likely to add to the total distortion and in this transmitter it would be expected that any distortion component lying above 7,000 cycles will be increased by the use of 70 feed-back. Also, the gain reduction above this frequency will be less than at lower frequencies where the feed-back is 180° out of phase. This would cause the overall frequency characteristic 75 to rise about 7,000 cycles. One of the features

of this system is that the second path 62, 64, 66 may be so adjusted as to provide an excess of neutralizing voltage in the region of the "singing" frequency, and so lower the gain of the 5 first stage by degenerative feed-back action that the frequency characteristic may be made very uniform. This adjustment at the same time acts to degenerate high order distortion components which would lie in this case above 7,000 cycles 10 and so prevents their addition to the transmitter distortion in this range. The frequency characteristic may be used as a criterion for this adjustment and, of course, it is desirable that it be uniform.

15 Another means of securing the same result in a laboratory set-up is to measure the frequency characteristic with the feed-back loop open at the input to the first tube. In this case an audio oscillator of constant output would be fed in at 20 this point. A cathode ray oscilloscope may be connected so as to indicate the phase and amplitude relations existing between the oscillator voltage and the voltage appearing across the combination of the two paths. In this case the 25 second path is adjusted both in phase and in amplitude so that the amplitude and phase characteristic is uniform or reasonably so over the wanted frequency band. When this adjustment is completed, the feed-back loop may be joined 30 and the frequency characteristic of the transmitter will be found uniform.

Having thus described my invention, what I claim is:

35 1. In a radio transmitting system wherein audio frequency waves are amplified, wherein radio frequency waves are generated, wherein the amplified audio frequency waves are used to amplitude modulate the generated radio frequency waves and wherein an undesirable hum component is present in the modulated waves due to energization of tubes in said transmitter with currents derived from a low frequency alternating current source, the method of reducing 40 the hum component which includes rectifying the portion of the modulated waves so as to obtain a copy of the audio frequency waves and hum introduced at the transmitter, feeding back the rectified waves for reamplification with the 45 audio frequency waves so that the hum component is appreciably reduced and degeneratively combining parasitic frequency waves with waves fed back for hum reduction so as to prevent undesirable parasitic oscillation generation at frequencies beyond the usable frequency range of 50 the transmitter.

55 2. In a radio transmitting system for transmitting amplitude modulated waves with a substantial reduction in hum and distortion, an audio frequency amplifier, a radio frequency generator, a modulator, means for feeding waves from said generator and amplifier to said modulator, a power amplifier coupled to said modulator and serving to amplify amplitude modulated waves derived from said modulator, means for energizing the cathode of a tube in said power amplifier with currents derived from a low frequency alternating current source, means for supplying the anode of a tube in said power amplifier with a rectified current derived from a low frequency alternating current source, the excitation of said tube serving to introduce undesirable hum and distortion in the output of said power amplifier, means for reducing said hum and distortion components comprising a rectifier

coupled to the output of said power amplifier and means for feeding back in reversed phase to said audio frequency amplifier rectified currents derived from said rectifier whereby hum and distortion are reduced with concomitant tendency 5 to produce parasitic oscillations at frequencies beyond the usual audio frequency range, and means for preventing the generation of parasitic oscillations comprising a circuit connected between said audio amplifier and the rectifier for 10 feeding into the rectifier feed-back path a voltage which is cophasal with the rectified voltage over a range including the useful audio frequency range and for feeding into the rectifier feed-back circuit a voltage which is substantially equal and 15 opposite in phase to parasitic frequency voltages appearing in the output circuit of said rectifier which would otherwise tend to produce undesired parasitic oscillation generation.

20 3. Apparatus as claimed in claim 2, characterized by the fact that each of the stages of the transmitter contains a tube whose cathode is energized with currents derived from a low frequency alternating current source and whose anode is supplied with voltage derived from a 25 rectified low frequency alternating current, and being further characterized by the fact that the rectifier output is fed back to an early point in the audio frequency system of the transmitter and that a feed-back path for preventing parasitic oscillation generation is connected to a later 30 point in the audio frequency system and being further characterized by the fact that the parasitic oscillation generation prevention path includes a resonant circuit resonant at some frequency beyond the working audio range of the transmitter.

35 4. In a radio transmitting system wherein audio frequency waves are amplified, wherein radio frequency waves are generated, wherein the amplified audio frequency waves are used to amplitude modulate the generated radio frequency waves and wherein distortion components are present in the modulated waves, the method of reducing the 40 distortion components which includes rectifying a portion of the modulated waves so as to obtain a copy of the audio frequency waves and distortion, feeding back the rectified waves for reamplification with the audio frequency waves so that the distortion components are reduced and degeneratively combining parasitic frequency waves with waves fed back for distortion reduction so as to prevent undesirable parasitic oscillation generation at frequencies beyond the usable frequency 45 range of the transmitter.

50 5. In combination, a source of modulating waves, a source of carrier waves, means for modulating waves from said carrier wave source with waves from said modulation wave source, means for feeding said waves to an output circuit, a rectifier for rectifying a portion of the modulated waves appearing in said output circuit, means for feeding the output of said rectifier in degenerative phase into said source of modulating waves so that distortion products appearing in the output 55 circuit are reduced, and means for feeding waves of distortion frequencies into said feed-back means in such phase as to substantially eliminate regeneration effects at distortion frequencies.

55 6. In combination, a bridge circuit, means for feeding modulation potentials across two conjugate points of said bridge circuit, a modulation amplifier connected unsymmetrically to said bridge, means utilizing the output of said modulation amplifier to modulate carrier waves, means 70

for rectifying a portion of the modulated carrier waves, means for feeding the rectified carrier waves in degenerative phase to the other pair of conjugate points of said bridge, and means, associated with said last mentioned means, for preventing excessive unwanted regeneration at one or more frequencies at which excessive unwanted regeneration occurs.

7. Apparatus as claimed in claim 6, characterized by the fact that the means for preventing excessive regeneration includes a tuned circuit tuned to a frequency at which excessive regeneration would otherwise occur.

8. In a radio transmitting system having a modulation frequency amplifying circuit and a modulated high frequency output circuit, a rectifier coupled to said output circuit for rectifying a portion of the wave energy appearing therein, a feed-back circuit for feeding back the rectified energy to said modulation circuit, the feed-back being so adjusted as to be degenerative in phase and so as to reduce distortion components in said output circuit, and means connected with said feed-back means for minimizing and substantially preventing regenerative action at distortion frequencies whereby the energy in said output circuit is substantially confined in frequency to a desired range of frequencies.

9. In a radio transmitter having an audio frequency amplifier tube and an output circuit in which modulated high frequency waves appear, an audio frequency bridge circuit, means for coupling input electrodes of said amplifier unsymmetrically to said bridge circuit, means for applying audio frequency waves to a pair of conjugate points on said bridge circuit, a rectifier coupled to said output circuit, a resistance connected between the output electrodes of said rectifier, means including a condenser for applying the voltage drop across said resistance across the other pair of conjugate points of said bridge circuit, and a tuned circuit connected between terminals of said resistance for introducing into said resistance voltages opposing voltages in said resistance, which latter voltages tend to cause undesired effects in said radio transmitter.

10. In a radio transmitter having an audio frequency amplifying tube and an output circuit in which modulated radio frequency energy appears and circuits operatively connected between said audio frequency tube and said output circuit, a bridge circuit, means coupling the input electrodes of said audio frequency amplifier to one arm of said bridge circuit, means coupling audio frequency waves to be transmitted to a pair of opposite corners of said bridge, a rectifier coupled to said output circuit, a resistance connected between the output electrodes of said rectifier, means for feeding the voltage drop across said resistance in degenerative phase to the other opposite corners of said bridge, said means including a serially connected condenser, the arrangement as so far described being adjusted so as to cause disproportionate degeneration of distortion components appearing in said output circuit, and means for lessening the tendency towards regenerative amplification at frequencies lying beyond a desired operating range of frequencies, comprising a circuit connected from the output circuit of said audio frequency amplifier to the output circuit of said rectifier, said connecting circuit including a condenser, a resistance, and a circuit, connected across said degenerative feed-ing means, tuned to a frequency beyond the desired operating range.

11. Apparatus as claimed in claim 2, characterized by the fact that each of the stages of the transmitter contains a tube whose cathode is energized with currents derived from a low frequency alternating current source and whose anode is supplied with voltage derived from a rectified low frequency alternating current, and being further characterized by the fact that the rectifier output is fed back to an early point in the audio frequency system of the transmitter and that a feed-back path for preventing parasitic oscillation generation is connected to a later point in the audio frequency system and being further characterized by the fact that the parasitic oscillation generation prevention path includes a circuit of high impedance at some frequency beyond the working audio range of the transmitter.

12. In combination, a source of modulating waves, a source of carrier waves, means for modulating waves from said carrier wave source with waves from said modulation wave source, means for feeding said waves to an output circuit, a rectifier for rectifying a portion of the modulated waves appearing in said output circuit, means for feeding the output of said rectifier in degenerative phase into said source of modulating waves so that distortion products appearing in the output circuit are appreciably reduced, and means, connected to the foregoing apparatus, selectively responsive to and reducing feed-back at one or more frequencies at which the integrated phase shift through said feed-back means is undesirably regenerative.

13. Apparatus as claimed in claim 6, characterized by the fact that the means for preventing unwanted regeneration includes a circuit having high impedance to a frequency at which the unwanted regeneration occurs.

14. In a radio transmitting system having a modulation frequency amplifying circuit and a modulated high frequency output circuit, a rectifier coupled to said output circuit for rectifying a portion of the wave energy appearing therein, a feed-back circuit for feeding back the rectified energy to said modulation circuit, the feed-back being so adjusted as to be degenerative in phase and so as to reduce distortion components in said output circuit, and means connected with the foregoing apparatus for preventing excessive unwanted regenerative amplification at one or more frequencies at which the integrated phase shift throughout the system tends to produce excessive regeneration.

15. In a radio transmitter having an audio frequency amplifying tube and an output circuit in which modulated radio frequency energy appears and circuits operatively connected between said audio frequency tube and said output circuit, a bridge circuit, means coupling the input electrodes of said audio frequency amplifier to one arm of said bridge circuit, means coupling audio frequency waves to be transmitted to a pair of opposite corners of said bridge, a rectifier coupled to said output circuit, a resistance connected between the output electrodes of said rectifier; means for feeding the voltage drop across said resistance in degenerative phase to the other opposite corners of said bridge, said means including a serially connected condenser, the arrangement as so far described being adjusted so as to cause degeneration of distortion components appearing in said output circuit but having unwanted regenerative amplification at certain frequencies; and means for reducing said unwanted regenerative amplification at said frequencies

comprising a circuit including a condenser and a resistance connected from an output circuit of said audio frequency amplifier to the output circuit of said rectifier, and a circuit connected to said degenerative feeding means, said last-mentioned circuit having high impedance to a frequency at which unwanted regenerative amplification occurs.

16. In combination, a source of modulating waves, a source of carrier waves, means for modulating waves from said carrier wave source with waves from said modulation wave source, means for feeding the modulated waves to an output circuit, a rectifier for rectifying a portion of the modulated waves to reproduce waves corresponding to the modulation, means for providing feed-back of the produced modulation waves to the source of modulating waves in order to reduce distortion produced in the normal modulation frequency band, and means, connected with the foregoing apparatus, selectively responsive to a frequency at which feed-back may be so shifted in phase as to produce excessive regenerative amplification, for preventing said excessive regenerative amplification.

17. Apparatus as claimed in claim 16, characterized by the fact that said selectively responsive means comprises a resonant circuit.

18. In combination, a source of modulating waves, a source of carrier waves, means for modulating waves from said carrier wave source with waves from said modulation wave source, means for feeding the modulated waves to an output circuit, a rectifier for rectifying a portion of the modulated waves to reproduce waves corresponding to the modulation, means for providing feed-back of the produced modulation waves to the source of modulating waves in order to reduce distortion produced in the normal modulation frequency band, and means, connected with the foregoing apparatus, comprising a circuit of high impedance for frequencies above the modulation band of frequencies for reducing the feed-back for frequencies outside the normal modulation frequency band where the feed-back may be so shifted in phase as to become regenerative instead of degenerative in its effect.

19. In combination, a source of modulating waves, a source of carrier waves, means for modulating waves from said carrier wave source with waves from said modulation wave source, means for feeding the modulated waves to an output circuit, a rectifier for rectifying a portion of the modulated waves to reproduce waves corresponding to the modulation, means for providing feed-back of the produced modulation waves to the source of modulating waves in order to reduce distortion produced in the normal modulation frequency band, and means, connected to the foregoing apparatus, comprising a circuit, selectively responsive to one or more frequencies, where the feed-back may be so shifted in phase as to become regenerative instead of degenerative in its effect, to prevent excessive regeneration.

20. Apparatus as claimed in claim 19, characterized by the fact that said selectively responsive circuit comprises a resonant circuit.

21. In combination, a source of modulating waves, a source of carrier waves, means for modulating waves from said carrier wave source with waves from said modulation wave source, means for feeding the modulated waves to an output circuit, a rectifier for rectifying a portion of the modulated waves to reproduce waves corresponding to the modulation, means for provid-

ing feed-back of the produced modulation waves to the source of modulating waves in order to reduce distortion produced in the normal modulation frequency band, and means, connected to the foregoing apparatus, comprising a circuit of high impedance for frequencies below the modulation band of frequencies for reducing the feed-back for frequencies outside the normal modulation frequency band where the feed-back may be so shifted in phase as to become regenerative instead of degenerative in its effect.

22. In combination, a source of modulating waves, a source of carrier waves, means for modulating waves from said carrier wave source with waves from said modulation wave source, means for feeding the modulated waves to an output circuit, a rectifier for rectifying a portion of the modulated waves to reproduce waves corresponding to the modulation, means for providing feed-back of the produced modulation waves to the source of modulating waves in order to reduce distortion produced in the normal modulation frequency band, and means, connected to the foregoing apparatus, comprising a circuit of high impedance for frequencies above and below the modulation band of frequencies for reducing the feed-back for frequencies outside the normal modulation frequency band where the feed-back may be so shifted in phase as to become regenerative instead of degenerative in its effect.

23. A loop system comprising, a source of modulating waves, a source of carrier waves, means for modulating waves from said carrier wave source with waves from said modulation wave source, means for feeding the modulated waves to an output circuit, a rectifier for rectifying a portion of the modulated waves to reproduce waves corresponding to the modulation, means for providing feed-back of the produced modulation waves to the source of modulating waves in order to reduce distortion produced in the normal modulation frequency band, and means, connected with said loop system comprising a circuit of suitable impedance for reducing the feed-back for frequencies where the feed-back may be so shifted in phase through said loop system as to become regenerative instead of degenerative in its effect.

24. In wave transmitting apparatus, a loop system comprising a modulation wave amplifier, a source of high frequency oscillations, a modulator for combining waves from said amplifier and oscillator to produce modulated high frequency waves, a demodulator for demodulating a portion of the modulated waves and means for degeneratively feeding back demodulated waves to the modulation wave amplifier to reduce distortion; and a feed-back circuit connected to a portion of the modulation wave amplifier for reducing the gain of the loop system at at least one frequency for which the phase shift around the loop system is undesirably regenerative.

25. In wave transmitting apparatus, a loop system comprising a modulation wave amplifier, a source of high frequency oscillations, a modulator for combining waves from said amplifier and oscillator to produce modulated high frequency waves, a demodulator for demodulating a portion of the modulated waves and means for degeneratively feeding back demodulated waves to the modulation wave amplifier to reduce distortion; and a resonant circuit connected to the loop system so as to reduce feedback for at least one frequency for which the integrated

phase shift around the loop system produces unwanted regeneration.

26. In wave transmitting apparatus, a loop system comprising a modulation wave amplifier, a source of high frequency oscillations, a modulator for combining waves from said amplifier and oscillator to produce modulated high frequency waves, a demodulator for demodulating a portion of the modulated waves and means

for degeneratively feeding back demodulated waves to the modulation wave amplifier to reduce distortion; and a parallel tuned circuit connected to the loop system so as to reduce feedback for at least one frequency for which the integrated phase shift around the loop system produces unwanted regeneration.
